Patented Apr. 27, 1915.

UNITED STATES PATENT OFFICE.

WILLIAM D. McCORMICK, OF UNIONTOWN, PENNSYLVANIA, ASSIGNOR OF ONE-HALF
TO ROBERT W. PLAYFORD, OF UNIONTOWN, PENNSYLVANIA.

GANG-PLANK.

1,137,645.

Specification of Letters Patent. Patented Apr. 27, 1915.

Application filed April 6, 1914. Serial No. 830,016.

To all whom it may concern:

Be it known that I, WILLIAM D. McCORMICK, a citizen of the United States, residing at Uniontown, in the county of Fayette and State of Pennsylvania, have invented 5 new and useful Improvements in Gang-Planks, of which the following is a specification.

This invention relates to improvements in 10 gang planks, such as are used for bridging the space between adjoining cars, between a car and an adjoining warehouse, or in similar environments; and the object of the invention is to provide a gang plank of simple, inexpensive and durable construction 15 which is equipped with means for preventing its longitudinal and lateral displacement, the said means being self-adjusting for the various inclinations at which the 20 plank may be arranged.

An embodiment of the invention is illustrated in the accompanying drawings in which:—

Figure 1 is a top plan view of a gang plank 25 in which the features of the invention are incorporated; Fig. 2 is a side elevation thereof drawn to a somewhat larger scale; and Fig. 3 is a detail sectional view on the line 3—3 of Fig. 1.

Similar characters of reference designate 30 corresponding parts throughout the several views.

The gang plank consists of the plank proper, designated generally by the numeral 35 1, and preferably in the form of a metal plate of suitable dimensions, having its upper surface suitably corrugated to prevent those who walk across the plank from slipping. The plank 1 is provided at each side 40 thereof with a brace, designated generally by the numeral 2, the office of which is to hold said plank against retrograde displacement. Each brace 2 comprises a U-shaped 45 clip 3 which is fitted upon the side edge portion of the plank and has at its outer side a laterally projecting post 4; a lever 5 pivotally mounted upon said post, a V-shaped jaw 6 pivotally connected to the outer end of the lever and removable in the plane of the 50 lever, a nut 7 threaded upon the post 4 to prevent lateral displacement of the lever 5 relatively to the clip 3, and a pin 8 to prevent displacement of the clip 3 relatively to the plate 1. The plate 1 has at each side 55 thereof a longitudinal row of openings 9,

each row of openings being preferably co-extensive with the length of the plate, and the pin 8 is inserted through any selected one of the openings 9 and through alining openings 10 in the legs of the clip 3. Obviously, when the pin 8 is removed the clip 3 may be adjusted lengthwise of the plank as the circumstances may require. The office of the jaw 6 is to engage the sill or floor adjacent the lower end of the plank and the said 60 jaw has its arms arranged preferably at a 90° angle and provided with serrated gripping faces.

It is preferred to employ a means adjacent the upper end of the plank for preventing 70 displacement of the plank in an upward direction, and such means may conveniently consist of pins 11 inserted through suitable openings 9. It is preferred to connect the pins 11 and the pins 8 at each side of the 75 plank by chains 12, which chains pass loosely through openings in the reduced outer ends of the post 4. In this way the pins 8 and 11 are prevented from becoming lost and the nuts 7 are locked against displacement from the post 4. 80

By virtue of the features of construction described, the plank 1 is positively prevented from retrograde or lateral displacement consequent to the movements of the trucks 85 in transferring a load. It follows that the gang plank herein described promotes both safety and convenience in the transfer of a load from car to car or from car to warehouse, or vice versa. 90

The braces 2 are shown as adjacent the lower end of the gang plank, but in any event, they will engage the sill which will oppose a resistance to the strongest forces tending to produce a displacement of the 95 plank in the direction of its length.

By virtue of the relation of the link 5 to the clip 3 and to the jaw 6, the braces 2 adjust themselves to the different inclinations at which the plank may be set, and 100 moreover, are not affected by any springing action of the plank under the weight of the load. The braces may also be adjusted lengthwise of the plank to accord with the circumstances and conditions of use. 105

Having fully described my invention, I claim:

1. In combination, a gang plank and a brace at each side thereof, each brace including a post projecting laterally from the 110

- gang plank, a lever pivotally mounted on the said post and a sill-engaging jaw pivoted to the outer end of the lever for movement in the plane thereof.
- 5 2. In combination, a gang plank and a brace at each side thereof, each brace including a post projecting laterally from the gang plank and adjustable lengthwise thereof, a lever pivotally mounted on the said post and a sill-engaging jaw pivoted to the outer end of the lever for movement in the plane thereof.
- 10 3. In combination, a gang plank and a brace at each side thereof, each brace including a clip adjustable lengthwise of the gang plank and having a laterally projecting post, a lever pivotally mounted on said post and a sill-engaging jaw pivotally connected to the outer end of said lever for movement in the plane thereof.
- 15 4. In combination, a gang plank and a brace at each side thereof, each brace comprising a U-shaped clip fitted over the side edge portion of the gang plank and adjustable lengthwise thereof and having a laterally projecting post, a lever pivotally mounted on said post and a sill-engaging jaw pivotally connected to the outer end of said lever for movement in the plane thereof.
- 20 5. In combination, a gang plank and a brace at each side thereof, each brace comprising a U-shaped clip fitted over the side edge portion of the gang plank and adjustable lengthwise thereof and having a laterally projecting post, a lever pivotally mounted on said post and a sill-engaging jaw pivotally connected to the outer end of said lever for movement in the plane thereof.
- 25 6. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank.
- 30 7. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank, a nut mounted upon the outer end of the post to prevent displacement of the lever, and a chain carrying the pin and passing through an opening in the post beyond said nut.
- 35 8. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank, a nut mounted upon the outer end of the post to prevent displacement of the lever, and a chain carrying the pin and passing through an opening in the post beyond said nut.
- 40 9. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank.
- 45 10. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank.
- 50 11. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank.
- 55 12. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank.
- 60 13. In combination, a gang plank and a brace at each side thereof, each brace comprising a U-shaped clip fitted over the side edge portion of the gang plank and adjustable lengthwise thereof, the plank having a longitudinal row of openings at each side thereof, a clip having alining openings in its legs, and a pin for engagement through the openings in the clip and through any one of the openings in the plank.

In testimony whereof I have hereunto set my hand in presence of two subscribing witnesses.

WILLIAM D. McCORMICK.
